US00D809548S

(12) **United States Design Patent** (10) **Patent No.:** **US D809,548 S**
(45) **Date of Patent:** **** Feb. 6, 2018**

(54) **DISPLAY SCREEN OR PORTION THEREOF WITH GRAPHICAL USER INTERFACE**

(71) Applicant: **Apple Inc.**, Cupertino, CA (US)

(72) Inventors: **Freddy Anzures**, San Francisco, CA (US); **Greg Apodaca**, Mountain View, CA (US); **Sebastian Johannes Bauer**, San Francisco, CA (US); **Jonathan Dascola**, San Francisco, CA (US); **Alan C. Dye**, San Francisco, CA (US); **Christopher Foss**, San Francisco, CA (US); **Jonathan P. Ive**, San Francisco, CA (US); **Kenneth Kocienda**, San Jose, CA (US); **Lauren Kim Trottier**, San Jose, CA (US); **Wan Si Wan**, Sunnyvale, CA (US); **Giancarlo Yerkes**, Menlo Park, CA (US)

(73) Assignee: **Apple Inc.**, Cupertino, CA (US)

(**) Term: **15 Years**

(21) Appl. No.: **29/588,900**

(22) Filed: **Dec. 23, 2016**

Related U.S. Application Data

(63) Continuation of application No. 29/538,798, filed on Sep. 8, 2015, now Pat. No. Des. 775,649.

CLAIM

The ornamental design for a display screen or portion thereof with graphical user interface, as shown and described.

DESCRIPTION

FIG. 1 is a front view of a display screen or portion thereof with graphical user interface showing the claimed design; and,

FIG. 2 is another embodiment thereof.

The outermost broken lines in the figures show a display screen or portion thereof, and form no part of the claimed design. The other broken lines in the figures show portions of the graphical user interface that form no part of the claimed design.

FIGS. 1-2 are illustrated with white, light gray and dark gray shading to show contrasting appearance; no particular color is claimed.

1 Claim, 1 Drawing Sheet
